Inventor:
E. Austin Herr,

By Riordan & Riordan
Attys.

UNITED STATES PATENT OFFICE.

EDWARD AUSTIN HERR, OF PHILADELPHIA, PENNSYLVANIA.

EXPANSION JOINT FOR COMPOSITION FLOORING.

Application filed April 2, 1924. Serial No. 703,654.

To all whom it may concern:

Be it known that I, EDWARD AUSTIN HERR, of Philadelphia, in the county of Philadelphia and State of Pennsylvania, a citizen of the United States, have invented certain new and useful Improvements in Expansion Joints for Composition Flooring, of which the following is a specification.

This invention relates to means for accommodating expansion in composition or artificial stone floors and for preventing the formation of cracks therein.

Extended observation and experience has demonstrated that the structural cracks in composition or artificial stone floors are due to the expansion of the floor against rigid or fixed points or angles, such as are found on plinths, pilasters, elevators, stationary store fixtures, etc., and my invention has for its object the provision of a yielding body which will receive and accommodate the pressure normally exerted by the expanding floor, eliminating the splitting force of the point or angle and thereby preventing the formation of cracks.

My invention is illustrated in the accompanying drawing and will be hereinafter fully set forth.

In the drawing, Fig. 1 is a perspective view of a portion of a room having my improvement included therein.

Fig. 2 is a detail showing a portion of the floor in plan and a corner of a pillar in horizontal section with the invention applied thereto,

Fig. 3 is a section on the line 3—3 of Fig. 2,

Fig. 4 is a view, similar to Fig. 2, showing the invention applied to an angle,

Fig. 5 is a section on the line 5—5 of Fig. 4,

Fig. 6 is a plan view and Fig. 7 an elevation of the block shown in Figs. 2 and 3,

Figs. 8 and 9 are, respectively, a plan view and an elevation of the block shown in Figs. 4 and 5,

Figs. 10 and 11 are detail sections showing additional forms of blocks.

In the drawing, the reference numeral 1 indicates a floor of artificial stone, such as cement or other plastic material, 2 denotes a pillar, and 3 a wall. Where a composition floor is employed, a sanitary base board, 4, is usually provided against which the floor is laid. In carrying out my present invention, I provide a yieldable body of cork or other material having like resilient qualities which may be in the form of a strip 5 embedded in the floor and extending from wall to wall in any direction. The sides of the strip flare or diverge downwardly so that the material of the floor will overlap the same and aid in holding the strip in place. The strip may rest on the foundation or floor support and its top surface is flush with the floor surface so that it will offer no obstruction to safe and easy travel over the floor. While the material of the floor will anchor the strip in place, it will have sufficient substance to permit securing nails to be driven therethrough if desired.

Ordinarily, the floor is laid so as to abut the base board, but with my invention I insert a strip of yieldable material in the angle formed by the floor and the base board, as shown at 6. It will be readily noted that the side edge 7 of the strip is disposed obliquely so that the floor will overlap the same and hold the strip down while the top edge 8 is inclined downwardly and backwardly so that the base board will effect locking engagement therewith. The exposed face 9 of the strip preferably defines a concave arc in cross section to facilitate cleaning, although it may present any other desired contour.

In applying the invention to a corner, as shown in Fig. 2, the yieldable body is preferably given the form of a circular button or disk 10 having a sector segment at 11 removed whereby it may be fitted closely to the corner and intersecting sides of a pillar, pilaster or other object. The outer side edge of the disk or button is inclined downwardly and outwardly relative to its axis, as at 12, so that the material of the floor may overlie it and anchor the disk in place. In applying the invention to an interior angle, as in Fig. 4, the yieldable body is formed as a sector of a circle, as at 13, the radial edges 14 fitting against the walls of the angle. It will be obvious that the cut out portion, as shown in Fig. 8, may be used in an angle such as just described and shown in Fig. 4, for example, and the remainder of the button or disk, as shown in Fig. 6, utilized for exterior angles as shown in Fig. 2. The arcuate edge is shaped to underlie the floor material, as in the other forms previously described, and, as shown clearly in Figs. 3 and 110

and 5, the inner flat edges of the disks are inclined away from the pillar or the wall to define an open space, 15, to increase the capacity of the body to accommodate expansion in the floor.

In all the forms thus far described, the base of the body is continuous but it may be provided with a central groove, 16, as shown in Figs. 10 and 11, Fig. 10 showing 10 a strip similar to the strip 5, and Fig. 11 showing a corner strip similar to the strip 6. The groove 16, like the bevel of the flat edge portions of the disks, increases the yieldability of the resilient body, and should 15 be employed where the joint is laid over a beam or concrete, or a large area is to be covered.

Having thus fully described my invention, what I claim as new and desire to secure 20 by Letters Patent of the United States is:—

1. A resilient device for use in composition surfaces, said device having the form of a circular button or disk with a sector removed therefrom, the outer side edge of the 25 disk inclined downwardly and outwardly, and the inner flat edges of the disk inclined downwardly and away from the upper edge

thereof, substantially as and for the purpose set forth.

2. A resilient device for use in composition surfaces, said device having the form of a button or disk with a segment removed therefrom. 30

3. A resilient device for use in composition surfaces, said device having the form 35 of a circular button or disk with a segment removed therefrom.

4. A resilient device for use in composition surfaces, said device having the form 40 of a circular button or disk with a segment removed therefrom, the outer side edge of the disk inclined downwardly and outwardly, substantially as and for the purpose set forth.

5. A resilient device for use in composition 45 surfaces, said device having the form of a circular button or disk with a segment removed therefrom, the inner flat edges of the disk inclined downwardly and away from the upper edge thereof. 50

In testimony whereof I hereunto affix my signature.

EDWARD AUSTIN HERR.
